SEWING MACHINE

Ralph E. Ladue, Bronxville, N. Y., assignor, by direct and mesne assignments, to Mardel Corporation, Wilmington, Del., a corporation of Delaware

Application April 25, 1938, Serial No. 204,013

1 Claim. (Cl. 112—2)

This invention relates to sewing machines and has particular reference to sewing machines and work holders therefor whereby special stitching operations may be produced rapidly and effectively.

In my copending application Serial No. 135,636, filed April 8, 1937, now Patent No. 2,131,055, granted September 27, 1938, there is described a method of permanently attaching cuffs to the cuffless sleeves of an otherwise completed shirt after the sleeves thereof have been trimmed to the measured length of the wearer, less the effective width of the corresponding cuffs. The present invention relates to a machine for so attaching the cuffs to the sleeves by stitching after the latter have been trimmed as described.

In accordance with the invention, an automatic sewing machine is provided having a cuff and sleeve holding device, so that they may be stitched together in the manner described. In one form of the machine, the work holder is advanced by intermittent mechanism in synchronism with the movements of the needle so that the cuff is automatically stitched to the sleeve. Preferably both sleeves with the corresponding cuffs positioned in proper relation are so arranged on the work holder as to be stitched together in one operation. In another form of the machine of this invention, a frame for attachment to a standard sewing machine is provided in which the work holder for the cuff is slidably advanced by the usual work-feeding mechanism of the machine.

It will be seen that with the combination sewing machine and work holder of this invention a haberdasher may rapidly and securely apply the cuffs to the trimmed sleeves in the store in a very short time and, although the invention is particularly adapted for the purpose described, it is not limited to that use.

For a more complete understanding of the invention, reference may be had to the accompanying drawings, in which:

Figure 1 is a side elevation of the sewing machine of this invention shown partially in section as seen along the line 1—1 of Fig. 2;

Fig. 2 is a plan view thereof, with a portion of the stitching head broken away for clarity;

Fig. 3 is a fragmentary section as seen along the line 3—3 of Fig. 1 and illustrates the mechanism for advancing the work holder carriage;

Fig. 4 is a longitudinal section as seen along the line 4—4 of Fig. 2;

Fig. 5 is an enlarged cross-section of the work

holder carriage as seen along the line 5—5 of Fig. 2;

Fig. 6 is a plan view of a modification of the sewing machine of this invention with the stitching head broken away in the interest of clarity;

Figs. 7 and 8 are longitudinal sections therethrough as seen along the lines 7—7 and 8—8, respectively; and

Fig. 9 is a transverse section as seen along the line 9—9.

Referring to Fig. 1 of the drawings, numeral 10 designates a substantially conventional form of sewing machine having the stitching head 11, the reciprocating needle 12 driven by mechanism including shaft 13 connected to pulley and flywheel 14 driven by electric motor 15 through belt 16, all supported by the bed plate 17. The machine 10 is of the lock-stitch, preferably single needle type, and is provided with the usual shuttle mechanism beneath the bed plate 17, although, in the interest of clarity the shuttle mechanism is not shown, inasmuch as it is conventional, such as the oscillating shuttle type.

The bed plate 17 of machine 10 is supported on a frame 18 which is generally T-shaped in plan, as shown in Fig. 2, and is arranged in such a way that a standard bed plate 17 will fit on it without material change. The frame 18 is provided with the feet 19 and with a rear support 20 which is adjustable to compensate for irregularities in the supporting table or the like.

As is shown particularly in Figs. 1 and 5, the bed plate 17 of the machine 10 is provided with a transverse slot which continues into the frame 18 and is designated 21 in Fig. 2. A similar slot 22 is provided in the frame 18 and extends along the front of the bed plate 17 but does not intercept it.

Slidably mounted in slot 21 is a slide 23 and slidably mounted in slot 22 is a slide 24. The two slides 23 and 24 are connected together at their ends by bars 26, and this structure forms the carriage 25. Bars 26 also act as handles whereby the carriage 25 may be moved along the frame 18.

As shown particularly in Figs. 2 and 4, the end bars 26 are provided with flanges 27 to which are secured by screws 28 or the like, a pair of elongated plates of thin metal or the like, 29 and 30, which are also secured to the corresponding slides 24 and 23, respectively, and which are spaced apart at their inner edges to provide the slot 31 extending along the carriage 25 for the needle 12 of the sewing machine as it cooperates with the shuttle, not shown, but positioned be-

neath the bed plate 17 in the usual way. The plates 29 and 30 are spaced closely to the surface of the bed plate 17 and because they are of thin material and therefore relatively flexible, they are supported against material flexing along their inner marginal edges by a rail 32 on the frame 18, as shown particularly in Fig. 5.

Positioned adjacent the longitudinal inner edges of plates 29 and 30 along the slot 31 are spaced sets of sharp, upwardly-extending pins 33 and 33'. Near the center of the carriage 25 two pairs of such pins 33 are provided, one pair on one side of the slot 31 on plate 30 and the other pair on the opposite side of slot 31 on plate 29. At the opposite ends of the carriage two sets of three pins 33' each are positioned on opposite sides of the slot 31, one set on plate 30 and the other set on plate 29. The purpose of the pins 33 and 33' is to position the sleeve designated S in Figs. 2 and 5 in proper relation to the cuff designated C. As is shown particularly in Fig. 5 the cuff C is provided with a slot or pocket formed between the inner and outer layers of fabric that form the cuff C into which is adapted to be inserted the trimmed end of the sleeve S.

In assembling the sleeve S and cuff C on the carriage 25, the cuff C is first impaled on one of the pins 33 at the center of the carriage and then is stretched taut and impaled on any one or more of the pins 33' at the corresponding end of the carriage, depending upon the length of the cuff, which usually is provided in two or three sizes. The cuff C is properly positioned with respect to the slot 31 and the needle 12 by a guide 34 formed by upwardly turning the inner edge of the plate 29 along the slot 31 as shown in Fig. 5. The cuff C is accordingly laid on plate 30 with its slotted or pocketed edge engaging the guide 34 and it is then impaled in this position upon the corresponding pins 33 and 33' in the manner described. After the cuff C has been so positioned, the trimmed end of the sleeve S is inserted in the cuff slot or pocket as far as it will go, and the sleeve is then impaled upon corresponding pins 33 and 33'. So positioned the cuff C and sleeve S are in proper alignment to be evenly stitched together.

Additional means are preferably provided for holding the cuff C and sleeve S or either of them in the described position. In the preferred arrangement a thin clamp plate 35, extending along the slot 31 and of a length at least as wide as the length of the corresponding cuff, is secured on a shaft 36 journalled in bearings 37 formed on the slide 23. Preferably a handle bar 38 is also pinned to the shaft 36, so that the clamp plate 35 may be readily raised and lowered, the clamp plate 35 being provided with apertures to admit the pins 33 and 33' which, however, need not be materially longer than the thickness of the cuff.

In order to urge the plate 35 resiliently against the cuff C so as to clamp it securely against the plate 30, a spring 39 is connected to handle bar 38 and to the slide 23 and is displaced at one side of the shaft 36. When the clamp plate 35 is raised by lifting the handle bar 38, the spring 39, because of its displaced position, is moved beyond the center of the shaft 35 with a sort of toggle action, and thus holds the clamp plate 35 in elevated position, as illustrated in Fig. 4, so that the operator may freely insert and remove the cuff C. Stops 40 limit the elevated position of the clamp plate 35.

Two such clamp plates 35 are employed for

each cuff, both being mounted on the carriage 25 in the manner described. Likewise, substantially similar clamp plates 41 are mounted on the slide 24 for holding the sleeves S in place and operate in the same way as clamp plates 35, so that they need not be described in further detail.

The slide 24 is provided with a depending flange 42 having ratchet teeth 43 as shown in Fig. 3. Cooperating with the ratchet teeth 43 is a pawl 44, which is housed within a small chamber defined by a depending flange 45 on the bed plate 17 and a bottom plate 46, as shown in Figs. 1 and 3. The pawl 44 is free to slide within this chamber and carries a leaf spring 47 engaging the flange 45, so to normally urge the pawl 44 into engagement with the ratchet teeth 43, as shown in Fig. 3. The pawl 44 is provided with an aperture into which fits the spherical head 48 of an oscillating lever 49 mounted on a shaft 50 positioned beneath the bed plate 17 of the machine and journalled at one end in the frame 18 and at the other end in abutment 51 on the bed plate 17.

The shaft 50 is provided with a laterally extending lever 52 to which is pivoted the lower end of a connecting rod 53 fitted with an eccentric strap 54 at its upper end, which cooperates with the eccentric 55 mounted on drive shaft 13 of the machine 10. Thus, as the machine operates the eccentric 55 reciprocates connecting rod 53 in a vertical direction and, because of its lever connection with shaft 50, the latter is oscillated so as to reciprocate the pawl 44 by means of lever 49. The movement of the pawl 44 is synchronized with the reciprocation of the needle 12 in such a way that the carriage 25 is advanced the length of one stitch between each stitching operation of the needle 12 and the cooperating shuttle, i. e., the carriage 25 is advanced when the needle 12 is in raised position, and this movement of the carriage 25 is from right to left, as seen in Fig. 2.

For the purpose of releasing the carriage 25 for retraction to the right hand end of the frame 18 in order to begin a stitching operation, pawl 44 is disengaged manually from the ratchet teeth 43 by pressing the pawl button 56 projecting through a slot in the front of the frame 18 as shown in Figs. 1 and 3. The pawl 44 is manually held disengaged from the ratchet teeth 43 in this fashion until the carriage 25 is retracted to the extreme limit of its right hand position, which is determined by the engagement between a depending lug 57 thereon and an abutment 58 on the frame 18, as shown particularly in Figs. 2 and 4. A similar lug 59, shown in Fig. 2, on the right hand end of the carriage 25 engages the button 60 of an electric single throw, single pole snap switch 61 series connected in the circuit of the motor 15 for stopping the motor 15 at the end of the stitching operation. A second button 62 for the switch 61 projects from the front of the frame 18 whereby the electric motor 15 may be energized to start the stitching operation, and whereby button 60 is reset.

Referring to the modification illustrated in Figs. 6 to 9 inclusive, a standard high-speed, single needle, lock-stitch sewing machine is utilized without change, and the standard work feeding mechanism is employed for advancing the carriage as well as the work. In this arrangement the shuttle plate slide is removed and a correspondingly dimensioned and apertured tongue 65 on the frame 66 is substituted, this frame having longitudinal flanges 67 on which the bed plate 64 75

rests and which is secured to the bed plate 64 by means of set screws 68. The rear end of the machine is suitably supported as is usual. In the interest of clarity, the shuttle mechanism of the 5 sewing machine is not shown and the oscillating work feeders 69 are only partially shown in Figs. 7 and 9, but it will be understood that they are of conventional form and driven in the usual way.

The frame 66 is provided with longitudinal 10 slots 70 and 71, the latter slot having its bottom flush with the upper surface of the bed plate 64 of the machine as shown in Fig. 9, whereas the 15 guide rail 72, defining the rear edge of slot 71, extends over the top of the bed plate 64, as also 20 shown in Fig. 9. The front slot 70 extends past the front edge of the bed plate 64 and is disposed below the upper surface thereof so that slide 73 in rear slot 71 is at a higher level than slide 74 in front slot 70. As before, the ends of 25 20 slides 72 and 73 are connected by bars 75, and the carriage 76 thus formed is of a length sufficient to accommodate only one cuff, as compared to the two-cuff carriage 25 shown in Fig. 2.

Secured to the slides 73 and 74 is a thin metal 25 plate 78 extending upwardly at its rear edge to form a support 77 in case a double or French type cuff is employed. This plate closely overlies the bed plate 64 of the machine and, being thin and therefore somewhat flexible, is supported by a rail 79 on the frame 66. The plate 78 is provided with an elongated slot 80 of a width to accommodate the presser foot 81 of the 30 sewing machine, so that the presser foot 81 may cooperate with the work feeding devices 69 in the 35 usual way to advance the cloth relatively to the needle.

As before, the plate 78 is provided with up-standing pins 82 on which the cuff C' and the sleeve S' may be impaled and held in position 40 for the stitching operation. In order to aid the work feeding devices 69 to advance the carriage 76 through the agency of the intervening cloth, a spring motor 83, mounted on the frame 66 and connected by cord or light cable 84 to the carriage 76, may be provided. This partially wound 45 spring motor is further wound up when the carriage is drawn to its extreme right hand position, depending on the length of the cuff C', and when the machine is started, the spring motor 50 aids in drawing the carriage 76 to the left, as seen in Fig. 6. The cable or cord 84 connecting the spring motor 83 to the carriage 76 may be conveniently inserted in the space 85 provided 55 between the upwardly turned rear edge of the plate 78 and the slide 73, as shown in Fig. 9. In this arrangement no work clamps, in addition to the pins 82, are provided, although if desired work clamps similar to those identified by numerals 35 and 41 in Figs. 1, 2, 4 and 5 may be 60 employed. For accommodating round cuffs provided with buttons B, the plate 78 is provided with a slot 86 which serves as a gauge for properly positioning the cuff in respect to the sleeve, particularly where two cuffs are mounted on the 65 same carriage, as in the arrangement of Fig. 2 where a button slot 86 shown on Fig. 6 is provided on opposite ends of the carriage.

In operation of the arrangements of Figs. 1 to 5 inclusive, the cuff C is first gauged by flange 34 70 and is then impaled on the pins 33 and 33' in the proper position. Where round cuffs with buttons are provided the button is placed in the slot 86. Then the sleeve S is inserted in the pocket or slot of the cuff C and impaled on the 75 corresponding pins 33 and 33'. The work clamp

35 is lowered and holds the cuff C in the proper relation to the sleeve and likewise the work clamp 44 holds the sleeve S in proper relation to the cuff C. So positioned the cuff and sleeve are ready for being stitched together by the needle 5 and shuttle mechanism of the machine, the operation of which begins with the carriage 25 in its extreme right hand position. The stitching head 11 and the needle 12 are thus located adjacent the extreme left hand end of the center 10 slot 31, their exact position being determined by the operator in accordance with the position of the corresponding end of the cuff C. In so positioning the carriage 25, the operator releases the pawl 44 by depressing button 56 and moves the 15 carriage by means of one of the handle bars 26. The motor 25 is then energized by actuation of button 62 which sets button 60 for engagement by the lug 59 on the carriage at the end of the stitching operation. The carriage 25 is accordingly advanced intermittently, between stitching movements of the needle 12 and shuttle, by the reciprocating pawl 44 cooperating with the ratchet teeth 43 on the carriage 25. The lock-stitching operation securely attaches the cuff to 20 the sleeve in a single operation. The sleeves with the attached cuffs are removed by raising work clamps 34 and 41 and the thread connecting the two sleeves is severed. The operation of the arrangement of Figs. 6 to 8, inclusive, is similar 25 and is readily understood from the foregoing description.

While certain preferred embodiments of the invention have been illustrated and described herein, it is to be understood that the invention 35 is not limited thereby, but is susceptible of changes in form and detail within the scope of the appended claim. For example, instead of moving the work holding carriage relatively to the stitching mechanism, the latter may be 40 driven relatively to the work holder, and the plates 29 and 30 may be joined as a single plate having the narrow needle slot 31 similar to plate 78, and the like. Also, where the carriage 76 of the arrangement of Figs. 6 to 9, inclusive, is sufficiently light in weight to be driven wholly by the work feeders 69 without the aid of the spring motor 83, the latter may be omitted so that the carriage may be readily removed from the frame 66 for the purpose of more conveniently attaching the cuff and sleeve thereto, and then inserting the carriage in the slots 70 and 71 for the stitching operation.

I claim:

In combination with a sewing machine for 55 stitching a cuff to the sleeve of a shirt, said cuff having a pocket for the reception of the end of the sleeve, a carriage having an elongated slot for the passage of the needle of said machine, means on the carriage for securing the cuff thereon with the inner edge of the cuff overlapping said slot, a gage flange on said carriage projecting from and extending along an edge of said slot for engagement by the said inner edge of the cuff to position the same in said overlapping relation with said slot, means on the carriage for securing the shirt sleeve thereon with the free end thereof overlapping said slot and the inner end of the cuff and inserted in the pocket of the cuff, means for actuating the sewing machine, 60 and means simultaneously engaging opposite surfaces of said cuff for relatively moving said carriage and machine for stitching said cuff and sleeve together in said overlapped relation.
